UNITED STATES PATENT OFFICE

2,582,457

BOBBY PIN HOLDER AND OPENER

Wert E. Roberts, La Junta, Colo., assignor of
fifty per cent to Robert F. Cadwallader, Rocky
Ford, Colo.

Application May 13, 1949, Serial No. 93,167

3 Claims. (Cl. 132—1)

1

This invention relates to a bobby pin dispenser, and has for its principal object the provision of a neat, simple, and highly efficient device which will hold a plurality of bobby pins in convenient position to be picked up by a beauty operator, and which will deliver each pin in the opened, ready-to-use position.

Another object of the invention is to provide a receiver for bobby pins into which they may be placed as they are removed from the hair, and which will receive and hold the bobby pins in individual, separated position.

A further object is to so construct the device that it may be folded into a thin, flat package which can be easily placed in a dresser drawer when not in use, and which will attach itself to a dresser top in convenient position when in use.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a plan view of the improved bobby pin holder, illustrating it in position for use;

Fig. 2 is a side view thereof;

Fig. 3 is an end view thereof; and

Fig. 4 is an enlarged, fragmentary sectional view, taken on the line 4—4, Fig. 2.

The device is designed for receiving, holding, and opening hair pins of the type known as "bobby pins," such as illustrated at 10 in the drawing.

The improved dispenser is preferably formed from transparent plastic of a type which can be readily cleaned and sterilized. It consists of a base plate 11 provided with rubber vacuum cups 12 having flanged necks 13 which are inserted through and expand in openings in the base plate 11. Two U-shaped receiving channels 14 are cemented to or formed integrally with the base plate 11 so as to project upwardly therefrom in alignment with each other along the medial line thereof.

An elongated receiving slot 15 is formed in the base plate 11 at each side of, and parallel to, the channels 14. The holders, per se, consist of T-shaped carrier strips 16 provided with longitudinally extending, vertical legs 17. The strips 16 support a plurality of spaced-apart, par-

allel, vertical partition teeth 18 which may be cemented to the strips 16 or molded integrally therewith.

The upper portion of the adjacent teeth 18 are joined by means of vertical separating members 19 having flat side faces. The separating members 19 are relatively thin so that the teeth project laterally from the separating members. The two legs of the pins 10 pass downwardly, on opposite sides of the separating members 19, and are maintained in parallel alignment by means of the teeth 18.

The teeth 18 are set rearwardly on the T-shaped strips 16 so that the forward portion of the strip 16 projects beyond the vertical leg 17. The slots 15 are designed to receive this projecting portion so that the holders may lie flat upon the base plate 11, where they will be maintained in position by means of the slots 15.

Let us assume that a beauty operator desires to use the device. She places one of the holders upright in the receiving channels 14 by inserting the vertical leg 17 thereof into the receiving channels 14. She then reaches for each pin successively and before removing the pin, tilts it either forwardly or backwardly, as shown in broken line in Fig. 3, to cause the separating members 19 to separate the two legs of the pin. The separated or opened pin is then grasped between the thumb and forefinger and held in the open position until it is in place in the hair. As the separating members 19 are spaced upwardly from the strip 16 the legs of the pins may pass through the space between the separators and the strip as the pins are tilted and ample room is provided for downward flexing of the lower legs of the pins. It should also be noted that as the teeth 18 are thicker than the separators they project from the separators laterally thereof, as shown in Figures 3 and 4, and when the pins are tilted towards the upward position indicated by the dotted lines in Figure 3 the wide side faces of the teeth will prevent the pins from twisting horizontally upon upper and lower edges of the separators and springing off of the separators before they are reached by the fingers of the operator and becoming lost.

After all of the pins in one holder have been used, it is laid on the base plate 11 with its strip 16 in one of the slots 15, and the other holder is placed in the vertical position in the receiving channels 14 ready for use.

When the pins are removed from the hair, they are simply forced downwardly upon the separating strips 19 which act to wedge the two legs

apart and support the pins in vertical, spaced-apart position ready for use.

For storage, both strips 16 are laid upon the base plate, with their projecting edges engaged in the slots 15 so as to present a relatively thin, portable package.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A device for supporting and for spreading the legs of a bobby pin comprising: a carrier strip; a plurality of vertical, spaced-apart partition teeth extending from said carrier strip; and separating members joining the upper portions of the adjacent teeth and spaced upwardly from the carrier strip, said separating members having less thickness than said teeth and adapted to pass between the legs of a bobby pin as it is forced downwardly thereover between the adjacent teeth, and said teeth projecting laterally from the separating members and serving to guide tilting movement of pins about the separating members.

2. A device for supporting and for spreading the legs of a bobby pin comprising: a carrier strip; a plurality of vertical, spaced-apart partition teeth extending upwardly from the carrier strip; and separating members joining the upper portions of the adjacent teeth and spaced upwardly from the strip, said separating members having flat side faces and being of less thickness than said teeth and adapted to pass between the legs of a bobby pin as it is forced downwardly thereover between the adjacent teeth, the space

between said teeth below said separating members being unobstructed so that a bobby pin may be tilted sidewardly thereon between the teeth and pass through the space and allow said separating members to separate the legs of the pin.

3. A device for supporting and for spreading the legs of a bobby pin comprising: a plurality of vertical, spaced-apart partition teeth; separating members joining the upper portions of the adjacent teeth, said separating members being of a thickness adapting them to pass between the legs of a bobby pin as it is forced downwardly thereover between the adjacent teeth and the teeth projecting laterally from the separating members to provide portions guiding tilting movement of pins across the separating members, the space between said teeth below said separating members being unobstructed so that bobby pins may pass through the spaces as they are tilted about the separating members to cause said separating members to separate the legs of the pins; a strip secured along the bottoms of and supporting said partition teeth; a base plate, and means for removably supporting said strip above said base plate in position to maintain said partition teeth vertical.
